UNITED STATES PATENT OFFICE.

BENJAMIN ROTTENBERG, OF NEW YORK, N. Y.

LOCK FOR COLLAPSIBLE EGG-CASE FILLERS.

1,412,709.

Specification of Letters Patent. Patented Apr. 11, 1922.

Application filed February 16, 1921. Serial No. 445,399.

To all whom it may concern:

Be it known that I, BENJAMIN ROTTENBERG, a citizen of the United States, and a resident of the city of New York, borough 5 of Manhattan, in the county and State of New York, have invented a new and Improved Lock for Collapsible Egg-Case Fillers, of which the following is a description.

My invention relates to a collapsible cellular filler for egg cases. The filler in question is made up of crossed slotted strips, the crossing strips defining the cells. The particular filler to which my invention relates is the ordinary filler made collapsible for 10 convenience in shipping prior to being put to use. The breakage of eggs in transit I found is largely due to the collapsing of the filler and the breakage is largely on the outer rows of cells.

20 The general object of my invention is to provide locking means for engaging the filler in a manner to prevent it from collapsing.

Reference is to be had to the accompanying drawings forming a part of this specification, it being understood that the drawings are merely illustrative of examples of the invention.

Figure 1 is a plan view of a filler equipped 30 with my improved locking means;

Figure 2 is a section on the line 2—2, Figure 1;

Figure 3 is a plan view of the locking element before the bending of the tongue like locking members out of the plane of said element;

Figure 4 is a plan view of the locking element with the locking members bent from the position shown in Figure 3;

40 Figure 5 is a cross section on the line 5—5, Figure 4;

Figure 6 is a plan view showing my invention embodied in the "flat" which in practice is interposed between successive fillers of an egg case to sustain the eggs in each filler, the view showing my improved flat applied to a collapsible filler;

Figure 7 is a plan view of the flat with the locking members in the plane of the flat and 50 before they are bent from said plane for entering cells of the filler;

Figure 8 is a view similar to Figure 7 but showing a modified form of the invention as embodied in a flat;

Figure 9 is a plan view of the flat shown 55 in Figure 8;

Figure 10 is a plan view of a locking element in strip form on the order of the element shown in Figures 1 to 5 but modified to present locking members of the same character embodied in the flats shown in Figures 8 and 9;

Figure 11 is a view similar to Figure 10, showing a further modification of the strip form of locking element. 65

Referring more particularly at first to Figures 1 to 5, the filler indicated generally by the numeral A is of known form and made up of cross strips a, a' slotted to interlock in a well known manner. In order to hold 70 the egg filler against collapsing I provide (Figures 1 to 5) elongated locking elements 10 in the form of strips made of any suitable flat material or combination of materials preferably pasteboard or the like, and employed in plurality, two of said elements being employed on the filler in the illustrated example. The locking element or elements 10 may be placed on either the top or bottom of the filler and so disposed as to range from 80 one corner cell to the corner cell diagonally opposite. Each locking element 10 is formed with tongue-like locking members 11 adapted to enter obliquely opposite cells. The ends of the element 10 at the bases of the 85 locking members 11 are scored as at 12 to facilitate the bending and may have side slits 13 at the outer ends of said scored lines to insure the bending along given lines. The bending lines 12 are at right angles to each 90 other to correspond to two sides of a square cell and to converge at the medial line of the strips 10, and the locking members 11 are in corresponding planes. 95

The locking members 11 in Figures 1 to 5 are of such dimensions that they will lie along adjacent walls of a corner cell within the latter and at their bases the locking members 11 are of a width to correspond with the length of the adjacent walls and thereby 100 snugly fit between opposed walls of the cell to have a substantial bracing relation to said walls.

The blank, Figure 3, from which the strip 10 is formed, has cutouts 10^a at the ends of 105 V-shape so that the locking members 11 are of triangular shape and when bent downward on the scored lines 12, the inner side

edges of said locking members will meet at the medial line thereby bracing one another and bracing the adjacent walls of the filler, and consequently resisting collapsing strains 5 exerted on the filler.

In Figures 6 and 7 a flat 10^b is employed of an area to cover a filler and be interposed between adjacent fillers in the case. Said filler is shown as formed at the corners 10 with locking elements or tongues 11^a of triangular form, the bases of the tongues being parallel with adjacent side edges of the flat. Initially the tongues project beyond the adjacent side edges. The flat is 15 scored as at 12^a at the bases of the locking elements 11^a for the bending down thereof, the scores 12 being parallel with and inward from the planes of the adjacent side edges. The flat is slotted at the sides of 20 a pair of tongues as at 13^a, the slots extending inwardly to the scored lines 12^a, said slots being thus on parallel oblique lines so that the tongues are partly within the side edges of the flat and partly projecting beyond said side edges when the tongues 25 are in the plane of the flat and before being bent at substantially right angles thereto to enter the cells. The tongues 11^a are adapted to be entered in the corner cells 30 against the adjacent outer walls thereof to brace the same and lock the filler against collapsing after the manner of the tongues 11. The arrangement referred to results in 35 marginal edge portions 10^c between the respective corner locking members and adapted to overlie the filler over the whole area and at the sides thereof, so that the edge portions will not be pressed into the fillers by the weight of eggs above the flat.

40 In the form of flat shown in Figures 8 and 9, the locking elements are produced inwardly from the edges, the openings produced by the bending down of the elements being surrounded on all sides by the material of the flat. The locking elements 11^b of Figures 8 and 9 are so disposed as to lie at the inner adjacent sides of the corner cells instead of within said corner cells as in the previously described constructions, in 45 order to brace the sides of the cells adjacent to which said locking elements are disposed. To produce the triangular locking elements 11^b, I produce slits 13^b at an obtuse angle to each other and a slit 13^c 50 transverse to the first-mentioned slits at the point of convergence of the latter. Also, the material is scored as at 12^b at the bases of the elements 11^b.

In Figure 10 a locking element 10^c of strip 60 form corresponding generally with the locking element of Figures 1 to 5 is shown but in which the locking elements 11^c are of the form shown in Figures 8 and 9 and produced inwardly from the ends of the strip. 65 The slits 13^d, 13^e correspond with the slits

13^b, 13^c and the score lines 12^c at the bases of the elements 11^c correspond with the score lines of the other figures, particularly Figures 8 and 9. The end edges of the strip 10^c converge at the medial line to conform 70 to the corner cells when the strip 10^c is placed obliquely.

In the form shown in Figure 11 the locking strip 10^h is formed with locking members 10^g at the end produced by slitting the 75 strip longitudinally as at 13^d from each end along the medial line or approximately so and bending down the material at the sides of the slot on the oblique score lines 12^d, said score lines extending from the corners 80 and convergent at the medial line of the strip at the inner end of the slits 13^e.

I would state in conclusion that while the illustrated examples constitute practical embodiments of the invention, I do 85 not limit myself strictly to the mechanical details herein illustrated, since manifestly the same can be considerably varied without departure from the spirit of the invention as defined in the appended claims. 90

Having thus described my invention, 1 claim:

1. As a new article of manufacture, a device for use with a collapsible egg-case filler, consisting of an element adapted to lie at the top or bottom of the filler and having members adapted to be disposed in cells of the filler against and parallel with walls thereof to constitute a brace for resisting collapsing of the filler. 95

2. As a new article of manufacture, a device for use with a collapsible egg-case filler consisting of an element adapted to lie flat on a face of the filler over cells thereof and having locking tongues adapted to be disposed in positions to enter in cells of the fillers and lie against and parallel with walls thereof to constitute a brace for resisting collapsing of the filler. 105

3. As a new article of manufacture, a flat 110 for egg-case fillers having locking members adapted to enter cells of the filler to lock the same against collapsing, said locking members being disposed so as to lie along and parallel with two adjacent cell walls. 115

4. As a new article of manufacture, a locking element for collapsible egg-case fillers adapted to be disposed obliquely between diagonally opposite corners of the filler and having triangular locking members on the 120 ends thereof at a face of said element and adapted to be disposed in planes substantially at right angles to adapt them to enter diagonally opposite corner cells of the filler to lie against the adjacent outer walls of the said corner cells, the body of said element having end edges convergent at approximately the medial line of said element to conform to the planes of said locking members when in use, said locking members having a 125 130

width at their bases to fit snugly between opposite walls of the cell to have a bracing relation to the filler for resisting collapsing strains.

5 5. As a new article of manufacture, a locking element adapted to fit on a collapsible filler between diagonally opposite corners and having locking members to enter filler cells, said members adapted to be positioned to lie against and parallel with adjacent walls of the entered cells to brace the same and resist the collapsing of the filler.

10 6. In combination with a collapsible egg-case filler, of a locking strip disposed obliquely between diagonally opposite corners and having locking members entering into corner cells of the filler along adjacent walls of said corner cells, and having bracing relation to said filler to prevent collapsing 20 thereof.

15 7. The combination with a collapsible egg-case filler, of locking elements disposed obliquely between diagonally opposite corners and having locking members entering 25 into cells of the filler along adjacent walls

thereof, said locking members being of triangular form and having a width at their bases to lie along adjacent walls of the engaged cells and fit snugly between two opposite walls.

30 8. As a new article of manufacture, a locking element for a collapsible filler having V-shaped cut-outs in the ends thereof, and triangular locking members at the sides of said cut-outs and bendable to enter a corner cell of the filler and be disposed therein at right angles to each other along adjacent walls.

35 9. As a new article of manufacture, a locking element for a collapsible filler, said element being in the form of a strip adapted to be disposed obliquely on the filler at the top or bottom thereof, and triangular locking members on the strip at the ends, said members having their bases on oblique lines 40 convergent in an inward direction approximately the medial line of the strip, the members being bendable at an angle to the plane 45 of the strip to enter cells of the filler.

BENJAMIN ROTTENBERG.
